DESIGN FOR A DOUBLE-HEADED HATCHET

Malcolm W. Lewis, West Clarkesville, N. Y.

Application October 7, 1946, Serial No. 133,815

Term of patent 14 years

(Cl. D93—4)

To all whom it may concern:

Be it known that I, Malcolm W. Lewis, a citizen of the United States, residing at West Clarkesville, in the county of Allegheny and State of New York, have invented a new, original, and ornamental Design for a Double-Headed Hatchet, of which the following is a specification, reference being had to the accompanying drawing, forming part thereof.

Figure 1 is a view in side elevation of a double-headed hatchet showing my new design; and

Figure 2 is an end view in elevation showing my new design.

I claim:

The ornamental design for a double-headed hatchet, as shown.

MALCOLM W. LEWIS.
